(57) **CLAIM**

The ornamental design for a microphone boom for a communications headset, as shown and described.

DESCRIPTION

This application is related to co-pending U.S. Design patent application Ser. No. 29/190,651, entitled “Communications Headset” filed concurrently wherewith.

FIG. 1 is an upper front left perspective view of a microphone boom, the broken line drawings herein of communications headset as well as cord, connector, and clip for the communications headset are for illustrative purposes only and form no part of the claimed design.

FIG. 2 is a lower front right perspective view of the microphone boom of FIG. 1.

FIG. 3 is a left side elevational view of the microphone boom of FIG. 1.

FIG. 4 is a front elevational view of the microphone boom of FIG. 1.

FIG. 5 is a right side elevational view of the microphone boom of FIG. 1.

FIG. 6 is a rear elevational view of the microphone boom of FIG. 1.

FIG. 7 is a bottom plan view of the microphone boom of FIG. 1; and,

FIG. 8 is a top plan view of the microphone boom of FIG. 1.
